UNITED STATES PATENT OFFICE.

WILLIAM C. BAKER, OF NEW YORK, N. Y., ASSIGNOR TO THE BAKER HEATER COMPANY, OF NEW YORK.

SUPPORT FOR CAR-HEATER GRATES.

SPECIFICATION forming part of Letters Patent No. 380,544, dated April 3, 1883.

Original application filed April 18, 1885, Serial No. 162,625. Divided and this application filed June 22, 1886. Serial No. 205,839.
(No model.)

To all whom it may concern:

Be it known that I, WILLIAM C. BAKER, of the city and State of New York, have invented an Improvement in Supports for Car-Heater Grates, of which the following is a specification.

This application is a division of a former application for which a patent was granted to me December 7, 1886, No. 353,839; and the present invention relates to the construction of the lower portion of the car-heater, in which the ash-pit inclosure, bottom plate, and hearth are combined with a ring above the ash-pit having pendent loops closed at their lower ends, a triangular bracket having two arms passing into the pendent loops, with an intermediate third arm bearing upwardly against the under side of the ring, and horns projecting upwardly at the apex, and a grate having a central opening and cross-bar resting between the horns of the bracket, so that it can be shaken and swung thereon for dumping the ashes.

In the drawings, Figure 1 is a vertical section of the heater complete. Fig. 2 is a sectional plan view below the line *x*-*x*. Fig. 3 is a perspective view of the bracket for supporting the grate. Fig. 4 is a separate view through the grate and at right angles to Fig. 1, and

Fig. 5 is an inverted plan of the supporting bracket and of the center part of the grate.

The bottom plate, *K*, is provided with suitable legs or feet, by which it is to be bolted securely to the floor of the car, and this bottom plate, *K*, is nearly circular at one side; but at the other side it projects in the form of a concave hearth, *k*. Upon the surface of this bottom plate, *K*, is a circular recess or rib, receiving the segment of a cylinder, *H*, which in closes the ash-pit, except a comparatively narrow opening at the middle part of the hearth *k*, and there is a sliding segment or door, *h*, to close this opening, except when access is desired to the ash-pit, at which time this segment *h* is slid to one side.

Resting upon the segment *H* is the base-ring *C*, the central portion of which is open, and there is a circular range of openings around the same at *d*. The fire-pot *B* rests upon this base-

ring *C*, and there is a circular rib, *2*, upon this base-ring outside the fire-pot and between it and the casing *F*. The circular range of openings *d* is outside this casing *F*, and it is within the external jacket, *E*, so that there is an air-space between the jacket *E* and the case *F*, through which air ascends and passes out through openings *s* in the top plate, *S*, and this top plate, *S*, rests upon the case *F* and jacket *E*, and there are bolts at *4*, passing up through the base-ring *C* and through the top plate, *S*, by which the heater is firmly bolted to the floor of the car.

The safety-grate *U*, the escape-flue *T*, and the conical base *T* to said flue, and the parts therewith connected, being set forth in my aforesaid patent, are not herein claimed, and do not form a necessary part of this invention.

The portion of the ring *C* which projects inwardly inside the fire-pot *B* is sufficiently wide to form a support for the bottom of the heater or heater-coil *A*, and hence the open space in the middle of the ring *C* is of less diameter than the internal diameter of the said coil at the bottom thereof. This allows the circular grate *L* to be turned up edgewise in dumping the clinkers. At one side this ring *C* is notched, and the loops *n* hang below the notched portions.

The bracket *M* is triangular and terminates at the apex with two prongs or horns, *r s*. Two of the arms of the triangular bracket *M* drop into the pendent loops *n*, and the third arm of the said bracket passes back beneath the base-ring *C* and is turned upwardly, as at *o*. This allows for the removal of the bracket by lifting up the middle portion thereof, or for placing this bracket in the proper position by entering the end *o* beneath the ring *C* and dropping the other two ends of the bracket into the loops *n*.

The grate *L* is circular and provided with radial bars and with projecting teeth around its edge. At the center is an opening having a cross-bar, *p*, through it, which cross-bar passes in between the horns *r s*. Upon the under side of the grate *L* is a loop or mortise for the reception of one end of the T-shaped shaker *R*. By inserting this shaker the grate

can be swung horizontally a short distance, so as to shake down ashes, and when it becomes necessary to dump the fire or to remove clinkers the grate is swung upon the cross-bar *p* by the action of the shaker *R* until it stands almost vertically, as indicated by dotted lines, Fig. 4. In doing this the ashes are not thrown toward the front of the heater, but toward one side; hence they can be removed with facility by a shovel without falling upon the floor of the car, and the shape of the hearth is dishing, so that the risk of ashes falling over is lessened; but such ashes can be swept up and removed with facility from the hearth and ash-pit.

It will be seen that the foregoing advantages result from the bracket *M* extending to one side away from the front opening and hearth, as seen in Fig. 2, and being supported by the base-ring *C*, so as to allow for removing ashes

and clinkers without risk of their falling out on the car-floor.

I claim as my invention—

The combination, with the ash-pit inclosure *H* and bottom plate and hearth, of the ring *C* 25 above the ash-pit and having pendent loops closed at their lower ends, the triangular bracket having two arms passing into the pendent loops, and the intermediate third arm bearing upwardly against the under side of 30 the ring, and the horns projecting upwardly at the apex, and the grate having a central opening and cross-bar resting between the horns of the bracket, substantially as specified.

Signed by me this 18th day of June, A. D. 35 1886.

W. C. BAKER.
